UNITED STATES PATENT OFFICE.

CHARLES EDWARD DRUMMOND AND CHARLES RIDLEY, OF COVENTRY, ENGLAND.

MEANS FOR PRODUCING TEETH ON GEAR-WHEELS.

1,135,780.

Specification of Letters Patent.

Patented Apr. 13, 1915.

Application filed July 25, 1913. Serial No. 731,183.

To all whom it may concern:

Be it known that we, CHARLES EDWARD DRUMMOND and CHARLES RIDLEY, subjects of the King of Great Britain and Ireland, 5 and residing at Daimler Works, Coventry, in the county of Warwick, England, have invented certain new and useful Improved Means for Producing Teeth on Gear-Wheels, of which the following is a specification.

10 The present invention relates to the production of teeth on gear wheels and has for its object to form conjugate involute teeth by grinding in an improved manner.

It has been proposed to form involute 15 teeth by grinding, the gear wheel blank being rolled about a cylinder or cone along a plane tangential to the pitch circle.

The object of the present invention is to produce involute teeth by grinding in an 20 improved manner, and to provide means by which a greater area of the surface of the grinding wheel may be employed, and also to provide means whereby, by a simple adjustment, gear teeth of different sizes may 25 be readily ground in one and the same machine.

The invention consists in mounting the 30 grinding wheel in such a manner that it can be traversed to and from the plane along which the gear blank is rolling, whereby the 35 point of the grinding wheel in contact with the blank is moved to and fro in the radial direction, so that a larger area of the surface of the grinding wheel is made operative.

The invention further consists in rolling 40 the blank by means of one or more bands or wires carried by a slide, and in mounting the axis of the blank in a second slide, the 45 two slides being connected by a cross-bar so arranged that the relative amplitude of motion of the two slides can be varied as required to cut gear wheels of different sizes.

The invention further consists in the improved 50 method and means for grinding gear wheels with involute teeth hereinafter described.

Referring to the accompanying diagrammatic drawings:—Figure 1 is a view in a 55 plane at right angles to the axis of the wheel to be ground, showing the method of utilizing

ing a larger area of the grinding surface; Fig. 2 is a diagram of the mechanism for obtaining a rolling motion along various diameters of cylinders without changing the 55 diameter of the rolling cylinder; Fig. 3 is a plan showing the device for truing the face of the grinding wheel; Fig. 4 shows an alternative means for obtaining the relative movement of the gears being ground and the 60 controlling bands; Fig. 5 is an elevation of a machine for grinding bevel wheels; while Fig. 6 is a plan showing a gear blank mounted on a block suitable only for gear of a given size. 65

In the diagram Fig. 1, the gear blank is rolled on a plane *a b* tangential to the base circle, and the grinding wheel *c* is reciprocated with its axis *d e* always parallel to the plane *a b* between the positions shown 70 in full and dotted lines.

One tooth *f* of the gear wheel being ground is shown in full lines in the position it occupies when the grinding wheel *c* is in the position shown in full lines, and the 75 same tooth is shown in dotted lines at *g* in the position it occupies when the grinding wheel *c* is in the position shown in dotted lines, and it will be seen that by reciprocating the grinding wheel in a direction perpendicular to the rolling plane the whole area between the circles on the grinding surface passing through the points *h* and *k* is utilized, while a tooth of true involute 80 form is produced. 85

The rolling of the gear blank *l* is effected by mounting the blank in a suitable bearing in a slide *m* which can be traversed in a direction perpendicular to the grinding surface *n* of the grinding wheel *c*, which 90 rotates about the axis *d e* and the turning of the blank about its axis is effected by a steel band or bands *o* passing around and attached to a cylindrical surface *p* moving with the blank *l* and attached at its ends to a slide *q* 95 which is reciprocated in a direction perpendicular to the grinding surface *n* for the purpose of effecting the rolling.

The two slides *m* and *q* are connected together by a rod *r* passing through pivoted 100 guides *s t* carried by the slides *m q* respectively. The rod *r* is capable of movement

about a pivot u carried by a cross slide v which is moved to alter the ratio of amplitude of movement of one slide m relative to the other q . A suitable scale w is provided 5 to indicate the ratio of movement at which the apparatus is set.

It will be seen that in this arrangement, gear wheels of any size within certain limits and any pressure angle can be cut using 10 the same rolling cylinder, and in cutting spur gearing the side of the tooth will be of correct involute form, the cutting taking place along a line perpendicular to the line of rolling, and in the plane along which 15 the blank is rolled, and it will be seen therefore, that there is no necessity to traverse the work laterally across the grinding wheel, provided a grinding wheel of large enough diameter is used.

20 The machine may be conveniently arranged as shown in Fig. 3; the grinding wheel c rotates about a horizontal axis in bearings in a carriage capable of moving horizontally on slides 2. The gear blank l 25 rotates in a horizontal plane, being mounted on the spindle of a rolling cylinder p carried by a horizontally moving slide, and rotated by a second horizontally moving slide by means of bands, the slides being 30 connected together as shown in Fig. 2. In order to insure that the grinding face of the wheel c is accurate, a diamond or other truing tool 4 is provided on a carriage 5, 35 adapted to be fixed in a definite position in the machine.

When truing is required the grinding wheel c is moved parallel to its axis, until the grinding face is in contact with the diamond which is then traversed across the 40 face.

When the diamond has become worn, the carriage on which it is mounted is moved forward so that the acting face of the diamond comes against a fixed stop 6, so that 45 the diamond or like truing device forms a fixed point of reference in the machine.

In the modified form of gear motion shown in Fig. 4 the pivot for the rolling cylinder 11 and arbor for gear 12 to be 50 ground is mounted on the slide 13.

A reciprocating motion is given slide 13 by means of screw 14; this motion rolls the cylinder along the steel bands 15, as already described.

55 The feed screw 14 carries a pinion (or a rolling cylinder connected to steel bands may displace the rack and pinion) which engages with a rack carried on slide 16. The movement of slide 13 by screw 14 also gives 60 motion to slide 16, at right angles to 13.

On slide 16 is pivoted a slide 17, which may be set at any desired angle, and which operates through a slide block carried by slide 18. When this slide 17 is set at zero

or at right angles to slide 13, the movement 65 of slide 13 imparts no motion to slide 18, and this would be the correct setting for any gear having a base circle same diameter as rolling cylinder—for any gear greater or less in diameter, the slide 17 would be set to 70 angle required either to right or reduced roll to the gear by the movement of slide 18.

The two slides 16 and 18 may also be operated by means of screws as shown for 13, the two screws being geared together by a 75 set of change gears, which would give a ratio of movement required for any diameter of gear being treated—these gears would take the place of pinion, rack and slide 16 and 17, no gears being used when base circle 80 of gears equals rolling cylinder diameter.

Further, it will be seen that the same method may be applied to the cutting of bevel gear by rolling the blank on a cone instead of a cylinder as above described, the 85 correct involute bevel teeth being thus obtained. Apparatus suitable for carrying this out is shown at Fig. 5. The gear blank 1 is rolled on a cone about the axes 2, 3, by means of bands 4 carried by the slide 5, moved 90 longitudinally by a screw 20, the grinding wheel 6 being mounted with its axis horizontal. The rolling cone can be swung about an axis 7 to suit different sizes of gear, and change speed gears 8, connecting 95 the pinion 21 with the screw 20 are provided to give the correct rolling motion to the permanent rolling cone, to suit the particular gear which is being ground. The gear quadrant 9 driven by the pinion 21 carries the work head and arbor 10.

If desired, instead of using slides connected so that their relative movement may be altered, an arrangement as shown in Fig. 6 may be used, separate blocks 12 being provided, so that the gear blank is rolled upon a block having a rolling circle of suitable diameter for the size of gear required.

Having now described our invention what we claim as new and desire to secure by Letters Patent is:—

1. Means for generating involute teeth by rolling on a base circle, comprising in combination a grinding wheel, a blank carrying slide, a shaft carried by said slide, a rolling 115 drum on said shaft, means for carrying said blank on said shaft, means for oscillating said drum on said shaft, means for traversing said grinding wheel to and from the plane of rolling of said drum, whereby the 120 circular line of contact of the grinding wheel with the blank is moved to and fro in a radial direction, as set forth.

2. Means for generating involute teeth by rolling on a base circle, comprising in combination, a grinding wheel, a blank carrying slide, a shaft carried by said slide, a rolling drum on said shaft, means for car-

rying said blank on said shaft, a second slide, bands attached to said second slide and to said rolling drum, a pivoted cross bar adapted to connect said slides, the pivot of said bar being adjustable, as and for the purpose described.

In testimony whereof we have signed our

names to this specification in the presence of two subscribing witnesses.

CHARLES EDWARD DRUMMOND.
CHARLES RIDLEY.
